UNITED STATES PATENT OFFICE.

LEO VALENZIA, OF BALTIMORE, MARYLAND, ASSIGNOR TO THE MARYLAND TOY
MANUFACTURING COMPANY, INCORPORATED.

DESIGN FOR AN ASH-TRAY STAND.

58,202.

Specification for Design.

Patented June 21, 1921.

Application filed October 13, 1920. Serial No. 416,766. Term of patent 3½ years.

To all whom it may concern:

Be it known that I, LEO VALENZIA, a citizen of the United States, residing at Baltimore, in the State of Maryland, have invented a new, original, and ornamental Design for an Ash-Tray Stand, of which the following is a specification, reference being had to the accompanying drawing, forming part thereof.

The figure is a view in side elevation of an ash-tray stand embodying my design.

I claim:

The ornamental design for an ash tray stand, as shown.

LEO VALENZIA.
